UNITED STATES PATENT OFFICE.

JASON C. STEARNS, OF WORCESTER, MASSACHUSETTS.

SPOT-LIGHT.

1,256,606.

Specification of Letters Patent. Patented Feb. 19, 1918.

Application filed January 18, 1917. Serial No. 143,165.

To all whom it may concern:

Be it known that I, JASON C. STEARNS, a citizen of the United States, residing at Worcester, in the county of Worcester and State of Massachusetts, have invented a new and useful Spot-Light, of which the following is a specification.

The principal objects of this invention are to provide a spot light and switch entirely located within the main body of an exterior lamp casing; to provide an improved means for turning the spot-light on and off located at the rear of the lamp, and also to provide improvements in and simplification of the means by which the operating means and lamp are connected.

Reference is to be had to the accompanying drawings forming part of this application, in which—

Fig. 1 is a central sectional view of a spot-light showing this invention partly in section and partly in elevation;

Fig. 2 is a plan of the lamp fittings removed from the casing;

Fig. 3 is a side view of the same;

Fig. 4 is an end elevation, and

Fig. 5 is the opposite end elevation of the same, parts being shown in section on the line 5—5 of Fig. 3.

Fig. 6 is a view showing the flat end of the lamp casing, and the central cylindrical portion of the handle in section.

The lamp casing is shown as is usual in this class of lamps as consisting of an outer casing 23 and reflector 33, between which the supporting member for the lamp 34 is carried. In this case this supporting member comprises a hollow hub 35 secured on the back of the reflector 33 and constituting a split collar having a pair of parallel flanges 36 adapted to be secured together by a screw 37 to clamp it on a hollow sheet metal cylinder 38. This cylinder has the usual slots 39 for the projections on the lamp base and is also provided with a hard rubber or other insulating member 40 inside for carrying the conducting wires to the spring plungers 41 which conduct the current to the lamp.

Projecting from this hard rubber member 40 on opposite sides, preferably, is a pin 42 which serves two functions. In the first place a bifurcated skeleton metal member 43 is secured to the cylinder 40 by this pin which passes through holes in it, and in the second place the pin passes through two slots 44 arranged circumferentially on the cylin-

der 38. These slots are offset rearwardly at both ends so that as the member 43 is turned into either extreme position the hard rubber cylinder 40 is forced outwardly from the lamp. The operator then feels the resistance and knows the lamp is turned fully on or off. The springs of the plungers 41 force it back into the offset portions of the slot at each end of its travel. It will be noted that the plungers 41 move with this cylinder and that these slots limit the motion of the cylinder to a quarter turn. They are so arranged that in one extreme position the plungers are in contact with the lamp terminals and in the other extreme position they are ninety degrees from the same and out of contact, so that the lamp is turned off. It will be seen that the entire switch is located within the main casing 23 and not in a handle.

The member 43 extends out beyond the cylinder 40 and is provided with a non-circular key 50 at its end by which the lamp is turned on and off by the mechanism now to be described. The mechanism for operating the switch is supported by the casing 23 which has a flat perforated end. A sheet metal casing 46 or switch handle is located in axial alinement with the lamp casing 23 and centrally with respect thereto. This casing is provided with an integral flange 47, and it has a central cylindrical portion 48. The flange is for receiving a cap member 49. This member 49 is of sheet metal and is fixed on the casing 46 which is capable of being turned on its axis. It forms the end of the casing 23 and has a flat inner end fitting the same. The cylindrical portion is screw threaded and extends into the lamp casing to receive a holding nut 51 and spring washer 52 for clamping the parts rotatably in position.

The key member 50 is located inside these parts. It fits in a hole 45 in the member 48 and provides means whereby the member 43 can be turned back and forth by the casing 46—49.

It will be seen that the member 46—49 provides for conveniently turning the light on and off. In this way a simple and safe arrangement is made for manipulating the light, and the construction and assembly of the parts is cheap and convenient.

Although I have illustrated and described only a single form of the invention I am aware of the fact that modifications can be

made therein by any person skilled in the art without departing from the scope of the invention as expressed in the claims. Therefore, I do not wish to be limited to all the 5 details of construction herein shown and described, but what I do claim is:—

1. In a spot-light, the combination of a casing and an internal reflector spaced apart, a hollow metallic cylinder concentric therewith, said reflector having a hollow split hub on its rear surface for securing said cylinder therein, said cylinder constituting a socket for receiving a lamp base, a switch for the lamp located entirely within said 10 casing and comprising a cylindrical member inside the end of said cylinder having conducting plungers for engaging the lamp terminals when the lamp is in position in the socket, and means mounted on and extending 15 rearwardly from the casing for turning said insulating cylinder and thus turning the lamp on and off.

2. The combination of a lamp casing, a cylinder concentric therewith constituting a 20 socket for receiving a lamp base, a cylindrical insulating member having conducting plungers for engaging the lamp terminals when the lamp is in position in the socket, a skeleton member mounted on said socket 25 cylinder, means inside the casing for connecting said skeleton member with the insulating member to cause them to turn together, and means outside the casing for turning the skeleton member.

3. In a spot-light, the combination of a lamp casing and an internal reflector spaced apart, a hollow metallic cylinder concentric therewith, said reflector having a hollow-split hub on its rear surface for securing 30 said cylinder thereto, said cylinder constituting a socket for receiving a lamp base, an insulating cylindrical member inside the end of said metallic cylinder having conducting plungers for engaging the lamp 35 terminals when the lamp is in position in the socket, a skeleton member outside the conducting cylinder, means for connecting said skeleton member with the insulating cylindrical member to cause them to turn together, said metallic cylinder having a guide 40 for limiting the motions of the cylindrical insulating member, and means carried by the casing for turning the skeleton member.

4. The combination of a lamp casing, a 45 socket for receiving a lamp base, an insulating cylindrical member having conducting plungers for engaging the lamp terminals when the lamp is in position in the socket, a skeleton member connected with the insulating cylinder to cause them to turn together, said lamp socket having guide-slots 50 for limiting the motions of the cylindrical insulating member, said slots extending about one-quarter way around the same and 55 having offset portions at their ends extend-

ing away from the main body of the slot, and means for connecting the skeleton member and insulating member comprising a pin extending through the same and through both slots.

5. In a spot-light, the combination of a casing, a hollow metallic cylinder concentric therewith, said cylinder constituting a socket for receiving a lamp base, an insulating cylindrical member inside the end 70 of said cylinder having conducting plungers for engaging the lamp terminals when the lamp is in position in the socket, a skeleton member outside the insulating cylindrical member, means for connecting said skeleton member with the cylindrical member to cause them to move together, and means for turning the skeleton member comprising an auxiliary casing adapted to be turned on its own axis, and a key member turning with it 75 and arranged to engage and turn the end of the skeleton member.

6. The combination of a lamp casing having an axial end casing concentric therewith and oscillatable on its axis, said end casing 80 having a cylindrical portion at its inner end, means at the inner end of said end casing for turning a lamp in the casing on and off, a key member having means for turning the lamp operating means, and means on 85 said cylindrical end for turning the key member.

7. The combination of a lamp casing having a flat end and an axial end casing concentric therewith, with means at the inner end 100 of said end casing for turning a lamp in the casing on and off, comprising a key member, said end casing having a flat shoulder on its inner end fitting the flat end of the casing and having a threaded portion extending through said flat end, a spring washer and nut on said threaded portion inside the lamp casing, so that the end casing can be turned on its own axis for turning the lamp 105 on and off.

8. The combination of a lamp casing and an axial end casing or handle concentric therewith, with means at the inner end of said end casing for turning the lamp in the casing on or off, said means comprising a key 110 member, said end casing having a threaded portion extending through the lamp casing, and a nut on said threaded portion inside the lamp casing for holding the end casing, said end casing being rotatably connected 115 with the lamp casing so that it can be turned on its own axis independently of the lamp casing.

9. In a spot-light, the combination of a lamp casing having a socket for receiving a 120 lamp base, an insulating cylindrical member having conducting plungers for engaging the lamp terminals when the lamp is in position in the socket, means outside the insulating cylindrical member for turning the 125 lamp 130

lamp on and off, means for connecting said outside means with the cylindrical member to cause them to move together, an auxiliary casing mounted on the lamp casing and adapted to be turned on its own axis for turning said outside means, and a key member turning with the auxiliary casing and arranged to engage and turn the end of said outside means.

10. An electric switch connection including a socket, a lamp secured in said socket, having a contact point thereon, a removable insert in said socket, a contact on said insert in position to engage the contact on said lamp, a switch member adapted to engage and operate said removable insert, a lamp casing, an external switch handle, and means connected with said handle and extending through said casing for engaging and operating said switch member so as to make and break contact when said handle is operated.

11. An electric switch connection including a socket, a lamp secured in said socket, having double contact points, a removable

insert in said socket, contacts on said insert 25 adapted to engage said lamp, outwardly extending pins in said insert, a switch member adapted to engage said pins, a lamp casing, an external switch handle, and means connected with said handle and extending 30 through said casing for engaging and operating said switch member so as to make and break contact with said contact points when said handle is operated.

12. An electric switch connection including a socket, a lamp in said socket having double contact points, means for making and breaking contact with said points, a switch member having a bifurcated arm adapted to engage said means, and a switch 40 handle connected with said member whereby said member will operate so as to make and break said contact when said handle is turned.

In testimony whereof I have hereunto af- 45 fixed my signature.

JASON C. STEARNS.
